CLAIM

The ornamental design for an infrared heat reflector, as shown and described.

DESCRIPTION

FIG. 1 is a perspective view taken from the top, front and left side of an infrared heat showing our new design;

FIG. 2 is a left side elevation view thereof;

FIG. 3 is a top plan view thereof;

FIG. 4 is a right side elevation view thereof;

FIG. 5 is an enlarged front elevation view thereof, the rear being a mirror image of that shown;

FIG. 6 is a bottom plan view thereof.

FIG. 1

FIG. 2

FIG. 3

FIG. 4

FIG. 5

FIG. 6
